UNITED STATES PATENT OFFICE

WALTER D. TEAGUE, OF NEW YORK, N. Y., ASSIGNOR TO NATIONAL RADIATOR CORPORATION, OF JOHNSTOWN, PENNSYLVANIA, A CORPORATION OF DELAWARE

DESIGN FOR A COVER FOR BOILERS, HEATING FURNACES, WATER HEATERS, OR THE LIKE

Application filed May 17, 1932. Serial No. 43,825. Term of patent 14 years.

To all whom it may concern:

Be it known that I, WALTER D. TEAGUE, a citizen of the United States, residing at New York, in the county of New York and State of New York, have invented a new, original, and ornamental Design for a Cover for Boilers, Heating Furnaces, Water Heaters, or the Like, of which the following is a specification, reference being had to the accompanying drawings, forming a part thereof.

Figure 1 is a perspective view of a cover embodying my design, looking from one side thereof;

Figure 2 is a similar view looking from the opposite side; and

Figure 3 is a top plan view thereof.

I claim:

The ornamental design for a cover for boilers, heating furnaces, water heaters, or the like, as shown.

In testimony whereof I have hereunto subscribed my name this 9th day of May, 1932.

WALTER D. TEAGUE.
